EXCAVATOR

Thomas C. Mullins, Chicago, and William E. Mullins, Jr., Chester, Ill.

Application February 25, 1946, Serial No. 649,813

3 Claims. (Cl. 212—66)

1

This invention relates to improvements in excavating machines.

In excavating machines of the drag line or shovel type provided with a superstructure that swings about a vertical axis in depositing successive loads, a stationary circular rack or ring gear generally is provided in the lower deck or carriage substructure of the machine which, in cooperation with a number of motor driven pinions in the upper deck or superstructure, produces the swinging movement in the direction desired. The motors that drive the pinions that mesh with the circular rack generally are of the reversible type under control of the operator of the machine.

In large excavating machines of the type mentioned, such as are employed for example in strip mining and having booms from 100 to 185 feet in length that support buckets or dippers up to 30 or more cubic yards capacity, the stresses imposed on the pinions and racks are tremendous. In a single such machine used in strip mining the cost of repairs and replacements of pinions and racks has exceeded \$10,000.00 in a single year.

The rate of loading a shovel or dipper by an operator, and the time required for discharge by gravity of the loads are substantially fixed and hence attempts to increase the work done by a given machine generally have consisted in accelerating the rate of swing of the superstructure between successive loads. However, by accelerating the rate of swinging movement to and from load discharging positions, proportionally greater forces are imposed on the rack and gears, and hence the durability of the latter are a limiting factor in the earth moving capacity of the machine.

It is an object of the present invention to provide means whereby the swinging movements of such excavating apparatus can be accelerated and decelerated above the present safe or normal rate not only without imposing additional stresses upon the racks and pinions, but whereby such stresses may actually be reduced, and thereby not only directly increase the working capacity of the machine, but increase the capacity indirectly also by reducing the time lost by shutdowns for repairs referred to above.

In utilizing the improvements there is provided one or more controllable power units that operate propellers or air screws mounted on the machine for producing swinging efforts or forces that are additive to the forces delivered by the usual pinions that normally produce the swing-

2

ing movements of the superstructure which carries the bucket or dipper. In the accompanying drawings the structures shown are illustrative of the improvements.

5 Figure 1 is a side elevation of a drag line excavator provided with three power operated air screws or propellers which are so positioned and operable as to cooperate each with the other and with the conventional gear and pinion mechanism in swinging the superstructure about its vertical axis.

10 Fig. 2 is a broken top plan view of the power unit and propeller that are mounted on the outer end of the boom in Fig. 1, as viewed along line 15 2—2 of Fig. 1, such unit being similar to the other two units shown in Fig. 1, one near the rear end of the boom and the other at the rear end of the superstructure.

15 Fig. 3 is an enlarged broken top plan view of any one of the three propellers shown in Fig. 1, and illustrating in full and dotted lines two extreme positions of adjustment of the reversible pitch propeller blades whereby rotative movement of a propeller in a single direction can, by reversing the pitch of the blades, be caused to exert a swinging effort in a selected direction.

20 Fig. 4 is a side elevation of an excavator of the shovel type showing propellers arranged in opposed pairs for exerting swinging forces in either direction by the selected operation of co-operating propellers.

25 Fig. 5 is a broken top plan view of a pair of propellers and operating power units therefor shown at the outer end of the boom in Fig. 4.

30 Fig. 6 is a top plan view of the power units shown at the rear of the superstructure in Fig. 4.

35 Fig. 7 is a detached view of a propeller and driving unit therefor, comprising a reversible electric motor that may be employed in lieu of any of the other propeller units illustrated in the foregoing figures.

40 Fig. 8 is a diagrammatical view of another propeller driving unit.

45 In Fig. 1 of the drawing, 10 indicates generally an excavating machine of the drag line type comprising a swingable superstructure 11 and a substructure or carriage 12, which constitutes the mobile mechanism of the excavator. The superstructure 11 is supported on the carriage 12 for movement about a vertical axis indicated by line 13. The means for swinging the superstructure in either direction generally comprises a circular rack or ring gear 14 carried by the carriage 12 and a plurality of pinions carried by the superstructure 11. Such structure is con-

ventional and in Fig. 1 two pinions only are shown, although in some machines a greater number is employed. In Fig. 1 the pinions are indicated by the numeral 15. Each pinion is driven by a reversible motor 16, which is under the control of the operator of the machine.

Up to the present time manufacturers of such excavating machines, particularly of the larger type frequently used in strip mining operations, have been unable to provide gear and pinion structures which will withstand for substantial periods of time the tremendous stresses imposed on them, as referred to above. The present improvements contemplate the utilization of power units located on the machine at points substantially removed from the axis 13 for cooperation with the motor driven pinions 16 in accelerating and decelerating the swinging movements of the superstructure.

In Fig. 1 three such power units are shown. One of the power units, designated generally by the numeral 17, comprises an internal combustion engine 18 as shown in Fig. 2, which may be of an airplane type and which drives an air screw or propeller 19. Another such unit, indicated generally by the numeral 20, comprises a similar engine 21 which drives an air screw 22. Such unit is shown mounted at the rear of the superstructure. A third similar unit indicated generally by the numeral 23, comprises an engine 24 which operates a propeller 25. In the structure shown in Figs. 1, 2 and 3 the propellers are of the reversible pitch type, that is, of a type the blades of which may be reversed to produce movements forwardly and rearwardly.

Any suitable means under the control of the operator in the cab of the machine may be utilized for controlling the reversing movement of the propeller blades. Such control means 26 are indicated diagrammatically and may be electrical, hydraulic or mechanical, as preferred. By means of such control the blades of propellers 19 and 25 will exert moments in the same direction, while the blades of propeller 22 being on the opposite side of axis 13 will exert a moment in the direction opposite the direction of moments exerted by propellers 19 and 25, whereby the three propellers will mutually cooperate with the rack and pinion mechanism in producing swinging movement of the superstructure in one direction or the other under the control of the operator in the cab of the machine. Thus, when a bucket 27 has been loaded and elevation begun, the operator by manipulation preferably of a single control, will cause the motors of the three power units to accelerate from an idling speed to high speed or an intermediate speed in the proper cooperative directions for exerting forces that are additive to the forces exerted by the pinions 15 in swinging the superstructure in the desired direction. When the boom 28 of the machine has been swung to the point where the bucket 27 approaches or is over the selected position of discharge, the operator can reverse the pitch of the propeller blades of the three power units 17, 20 and 23 and thereby decelerate the swinging movement of the superstructure and thereby cushion or reduce the stresses normally imposed upon the rack and pinion mechanism. Upon the reversal of direction of operation of the pinions 15 the superstructure is started on its return to an excavating position aided by the auxiliary power units. The pitch of the propellers may again be reversed for decelerating and arresting the swinging movements of the superstructure at

the excavating position in cooperation with the control of the pinion operating motors 16. During the succeeding bucket loading interval the motors of the auxiliary power units merely idle or operate at a low speed. It will be seen that the forces exerted by the propellers are additive to those exerted by the pinions 15 in swinging the superstructure to and from load discharging position and thus relieve the pinions and the associated rack from a portion of the work otherwise required to be performed by them or enable the rate of swing to be accelerated and decelerated without imposing additional or unsafe loads on the pinions.

In Fig. 4 of the drawing there is illustrated an excavator of the shovel type that may be provided with propeller-power units similar to those described above with reference to Fig. 1. However, in Figs. 4 and 5 a somewhat different arrangement is shown which obviates the use of reversible pitch propellers in that at the outer end of the boom 29', as well as at the rear end of the superstructure 30 of the machine, there is shown propeller-power units arranged in pairs, as shown more particularly in Fig. 5. In Fig. 5 which is a top plan view of the propeller-power units shown at the outer end of the boom, two motors are shown arranged in axial alignment and having propellers adapted to exert oppositely directed forces. The motor 30 operates propeller 31 in a direction for causing swinging movement in one direction, while motor 32 operates propeller 33 for causing swinging movement in the opposite direction. The pair of motors which are shown mounted at the rear of the superstructure 29 are arranged similarly to the motors shown at the outer end of the boom. Thus, motor 34 operates a propeller 35 in a direction to exert a force in the same direction as that exerted by propeller 31. The motors 30 and 34 are designed to operate and to be controlled in unison, while motor 36 which operates propeller 37, exerts a force tending to swing the superstructure about its vertical axis in the same direction as that exerted by propeller 33. The motors 36 and 32 therefore are arranged to operate and to be controlled in unison.

The power units illustrated in Fig. 4 likewise are arranged for exerting forces which are additive to the forces exerted by the conventional motor driven pinions 38 which mesh with the circular rack 39, whereby the stresses imposed upon the rack and pinion structure are or may be reduced. The motors of the power units shown in Fig. 4 are controllable by any suitable means, electrical or otherwise, by the operator in the cab of the machine. Control means are indicated diagrammatically by numerals 40.

In Fig. 7 of the drawing a power unit is shown comprising an electrical motor 41 which drives a propeller 42. The motor 41 preferably is of the reversible type for operating the propeller in either direction for exerting a force in a selected direction. Power units of the type shown in Fig. 7 may, if desired, be substituted for the power units shown in the preceding figures, and when so used are controllable by conventional motor controls in the cab of the machine. In some instances, the electrically driven propellers may be of advantage in that they are readily controllable and can be supplied with current from any suitable source, as for example, from the same source from which the electrical power is derived for operating the excavating machines themselves when of the electrically operated type.

In Fig. 8 a further alternative structure is shown wherein an engine 43 is provided with a crank shaft 44 which at each end extends from the engine casing into operative relation with one of two clutches 45, 46 which are shown diagrammatically. The clutches when in driven engagement with the respective ends of shaft 44 are adapted to operate the propellers 47, 48 respectively. The propellers are selectively operable by operation of control means 49, 50 which extend from the clutches to the operator's station in the superstructure 51. The propellers are rotatable in the same direction and hence are oppositely pitched, one to provide swinging effort in one direction and the other to provide swinging effort in the opposite direction under control of the operator. The engine 43 in Fig. 8 is shown mounted on the outer end of a boom 52 which may correspond to either boom 28 or 29 shown in Figs. 1 and 4, respectively. Preferably a second engine having similarly clutch controlled propellers will be mounted at the rear of the superstructure for coaction with engine 43 in producing a swinging force on the superstructure in conjunction with the conventional swinging mechanism described above with respect to the preceding figures of the drawing.

The propellers employed as part of the power units need not be strictly of the airplane type, and where they are of the reversible pitch type it is desirable that they exert equal and maximum driving force in either position of extreme adjustment. Likewise the propeller employed in the electrical motor unit, such as is shown in Fig. 7, may be designed to exert equal driving force regardless of the direction of operation thereof.

While it is not contemplated that the auxiliary power units described need develop sufficient forces to swing the machine to and from load discharging positions independently of the conventional rack and pinion mechanism, the forces of such units being additive to the forces exerted by the rack and pinion mechanism relieve the latter of some of the stresses imposed thereon normally, and hence shutdowns by reason of breakage of such mechanism are reduced by the present improvements. Likewise, the mechanical advantage of the auxiliary units resulting from their being located as remotely as is feasible from the vertical axis of the superstructure enables such auxiliary units to accelerate and decelerate the normal rate of swinging movements of the superstructure, and hence to increase the earth moving capacity of a given machine by reducing the time intervals between successive loads.

While various structures illustrative of the improvements have been shown and described, various changes in mechanical details may be resorted to within the spirit of the invention.

We claim:

1. Excavating apparatus comprising a mobile carriage, a superstructure pivotally supported by the carriage for swinging movement on a vertical axis, said superstructure comprising a boom extending laterally therefrom, power operated mechanism on the carriage and superstructure for swinging the latter about said axis, and a power operated air screw mounted on said boom for exerting a force that is additive to the force exerted by said mechanism in swinging said superstructure.
2. Excavating apparatus comprising a mobile carriage, a superstructure pivotally supported by the carriage for swinging movement on a vertical axis, said superstructure comprising a boom extending laterally therefrom, power operated mechanism on the carriage and superstructure for swinging the latter about said axis, and power operated air screws, one mounted on said boom and the other on the superstructure on the side of the axis remote from the boom, for exerting forces in directions that are additive to the forces exerted by said mechanism in swinging the superstructure about said axis.
3. Excavating apparatus comprising a mobile carriage, a superstructure pivotally supported thereon for swinging movement about a vertical axis to and from excavating and load discharging positions, controllable mechanism for swinging said superstructure about said axis in either direction, and power units on said superstructure arranged in pairs on opposed sides of the axis of the superstructure, said pairs of units having air screws arranged for alternate operation for exerting forces in opposite directions that are additive to the forces exerted by said mechanism in swinging said superstructure in the respective directions.
